UNITED STATES PATENT OFFICE

LIDA S. ISAACS, OF EAGLE ROCK, CALIFORNIA, ASSIGNOR TO MRS. GEORGE D. GILMORE, MRS. ELAINE A. DUDLEY, AND MRS. ED C. MAGAURAN, ALL OF LOS ANGELES, CALIFORNIA, DOING BUSINESS UNDER THE FICTITIOUS FIRM NAME OF THE CALIFORNIA WOMEN OF THE GOLDEN WEST

DESIGN FOR A BADGE, PIN OR EMBLEM

Application filed March 13, 1931. Serial No. 39,073. Term of patent 14 years.

To all whom it may concern:

Be it known that I, LIDA S. ISAACS, a citizen of the United States, residing at Eagle Rock, in the county of Los Angeles and State of California, have invented a new, original, and ornamental Design for a Badge, Pin or Emblem, of which the following is a specification, reference being had to the accompanying drawings, forming a part thereof.

Fig. 2 is a side elevation thereof.

I claim:

The ornamental design for a badge, pin or emblem as shown.

Signed at Los Angeles, in the county of Los Angeles, and State of California, this 5th day of February, 1931.

LIDA S. ISAACS
